UNITED STATES PATENT OFFICE.

OLIVER L. LINK, OF ST. CHARLES, MISSOURI.

TRAP-DOOR.

1,265,686.

Specification of Letters Patent. Patented May 7, 1918.

Original application filed May 18, 1912, Serial No. 698,124. Divided and this application filed May 23, 1914.
Serial No. 840,493.

To all whom it may concern:

Be it known that I, OLIVER L. LINK, a citizen of the United States of America, residing at St. Charles, in the county of St. Charles and State of Missouri, have invented 5 certain new and useful Improvements in Trap-Doors, of which the following is a specification.

This invention relates to trap doors, and 10 is more especially designed for use in vestibule platforms of passenger cars, this being a division of my application filed May 18, 1912, Serial No. 698,124. One of the objects 15 of this invention is to construct a trap door of a single sheet of light metal which is reinforced by forming ribs thereon adjacent the edges thereof.

Another object is to provide improved 20 means for securing the door facing or floor- ing to the door.

Other and further objects will appear in 25 the specification, and be specifically pointed out in the appended claims, reference being had to the accompanying drawings exemplifying the invention, and in which,

Figure 1 is a plan view of this improved trap door, part of the flooring being broken away.

Fig. 2 is a cross section taken on the line 30 2—2, Fig. 1.

Referring to the drawings: 1 designates a trap door which is made of light weight sheet metal and is reinforced by the rectangular rib 2 which is formed adjacent the 35 edge of the door. This door is further reinforced by the pair of parallelly arranged ribs 3, said ribs merging at their ends into the rectangular rib 2. Formed between the ribs 2 and 3 are flat surfaces 4. Formed be- 40 tween the pair of ribs 3 is a flat surface 5.

This improved door is secured to the sill 6 by the hinge members 7, one portion 8 of 45 each of said hinge members being secured to said sill, and the other portions 9 thereof being secured to the under side of the door. Secured to the under side of the door against the flat surfaces 5 is a door operating mechanism 10, said mechanism 10 having a connecting rod 11 which is pivotally secured at 50 12 to the sill 6.

In constructing the reinforcing ribs 2 and 3, grooves 13 are formed on the door. These grooves are filled with a plastic material 14,

said material, when setting, adhering in the grooves. This plastic material provides 55 means for securing the flooring 15 to the door. The flooring is secured to the plastic material by nails 16 which are driven through said flooring and said plastic ma- 60 terial, said nails being somewhat longer than the depth of the grooves 13. As the pointed end of the nail engages the bottom of the groove, it will be deflected and turned, as shown at 17, which will cause the nail to 65 clutch the plastic material, thereby holding the flooring 15 securely in place. In order to hold the edges of the flooring 15 firmly against the trap door 1, edging strips 18 are secured to the edges of said trap door by 70 screws 19.

As it is desirable for trap doors of this character to be as compact as possible on account of being operatively mounted in a minimized space, it is necessary that the operating mechanism be situated as closely to 75 the under side of the trap door as possible. In this improved design of trap door, the door operating mechanism 10 is secured to the under side of the flat surface 5, thereby sitting very closely against the trap door so 80 that, when the door is opened, no objectionable parts will protrude into the descending passageway leading to the steps of a car.

If necessary, a pair of door operating mechanisms, such as 10, can be mounted 85 against the under side of the flat surfaces 4. The rectangular rib 2, being located adjacent the edges of the door 1, provides means for reinforcing the outer surfaces of the door, whereas the parallel ribs 3 serve to 90 reinforce the intermediate portion of the door. This design of reinforcing will provide means of constructing a trap door of light weight material.

What I claim is:

1. A trap door made from a plate of sheet metal, said plate having a rectangular rib formed thereon, and a pair of parallelly ar- 100 ranged ribs adjoining said rectangular rib, said plate having a flat surface formed be- 105 tween said pair of ribs, said flat surface pro- viding means of allowing a door operating mechanism to be engaged closely against the under side of said plate.

2. A trap door for vestibule platforms comprising a plate of sheet metal, said plate

being reinforced by a rectangular shaped depressed portion which is formed adjacent to the edges thereof, the central portion of said plate being without depressed reinforcing portions so as to provide a flat surface, said flat surface of said plate being for the reception of a door operating mechanism which is

to be engaged closely against the underside of said plate.

OLIVER L. LINK.
